UNITED STATES PATENT OFFICE.

KEMPFSTER B. MILLER AND CHARLES G. ASHLEY, OF CHICAGO, ILLINOIS, ASSIGNORS
TO McMEEN & MILLER, OF CHICAGO, ILLINOIS.

TELEPHONE-SUPPORT.

1,087,807.

Specification of Letters Patent.

Patented Feb. 17, 1914.

Application filed October 23, 1908. Serial No. 459,178.

To all whom it may concern:

Be it known that we, KEMPFSTER B. MILLER and CHARLES G. ASHLEY, citizens of the United States of America, and residents of Chicago, county of Cook, and State of Illinois, have invented a new and useful Improvement in Telephone-Supports, of which the following is a specification.

Our invention pertains to telephone supports, and provides a support for a desk stand or other telephone equipment, suspending the equipment flexibly so that it may be moved within certain limits; we provide for maintaining the telephone set plumb by attaching our support at a point near the top of the set, the set thus remaining plumb by its own weight.

The device of our invention comprises an arm pivoted to a swiveled base block, a spring so disposed as to balance the device and its supported telephone at all times, and proper devices of articulation for the attachment of the telephone set to the free end of the arm.

In the drawing, Figure 1 shows assembly of the device, complete with telephone set attached; Fig. 2 shows details of the lower end of the arm and of its mounting elements; Fig. 3 shows details of the parts at the outer end of the arm; Fig. 4 shows an alternative arrangement of parts at the outer end of the arm; and Fig. 5 shows an alternative arrangement of the spring.

Like numerals refer to like parts throughout the several views.

The anchor post 1 is designed to attach rigidly to a desk or wall or to any convenient object; this anchor post may be of any desired or convenient type, the sole requirement being that it comprise a vertical shaft 1' and shoulder 1'' to receive and sustain loosely and rotatably the base block 2. The movable arm of the device is preferably tubular, as shown, with lower and upper terminal castings, the lower casting 3 providing means for pivoting the tubular arm 4 to the base block, and the upper casting 5 providing means for attaching the telephone set to the outer end of the arm. An alternative desirable method of manufacture is to form or cast the movable arm in one piece comprising the equivalent of parts 3, 4 and 5. A spring 6 is attached to base block 1 at 20 and is attached at its other end adjustably to arm 4, the means of adjustment

suitable for use with a tubular arm 4 being shown in detail in Fig. 2. Inner tube 7 is shouldered to engage part 3; washer 8 rests upon the end of the inner tube 7; through washer 8 passes eye-bolt 9, secured adjustably by nut 10.

The design of the spring 7, for length and tension, and the distance of the eye 20 from the axis of the bolt 2' by which the arm is pivoted to the base block, shall be such as 60 to balance the arm and its suspended telephone set in any of the positions which the arm is likely to assume in swinging upon the pivot bolt 2'. The spring should be substantially without tension when the arm 65 is vertical, as shown in full lines in Fig. 1, and will increase its tension as the arm swings downward; the rate of increase of tension will depend upon the relations existing between the characteristics of the spring 70 and its rate of increase in length, and this should involve approximately a function of the angle which the arm makes with its vertical position; this approximation need not be extremely close, as it is desirable that the 75 joint at the bolt 2' have considerable friction, and the friction there shall be sufficient to annul any difference there may be at any time between the tendency of the telephone set to fall under the pull of gravitation, and the tendency to rise under the pull of the spring 6. An exact balance at all 80 times is impossible, since the weight of the telephone set upon the arm varies from time to time with the removal and replacement of 85 the receiver upon the switchhook.

In Fig. 5 a compression spring is used, engaging the part 2 and the washer 8, the washer 8 being adjustably connected to the part 2 by means of the rod 21 and the nut 95 10. At the outer end, the arm terminates in a yoke whose arms 5', 5'' support pivotally the swivel block 11, sustained by bolt 11'. Screw 12 and its locking pin 13 complete the assembly of this part. Swivel yoke 14 100 is adapted to be clamped between two structural parts of the telephone set, as parts 15 and 16; these may be any two parts convenient, and the lower end of yoke 14 shall be of a shape adapted to the requirements 105 of the parts between which it is to be clamped. In Fig. 4 the yoke 14' is complete and is clamped by the bolt which secures the transmitter to the column of a portable desk stand; in Fig. 3, one of the limbs of the 110

yoke is omitted, and the remaining limb is clamped between the transmitter lug 15 and the transmitter case 16. It is seen that a wide variation in the shape of the part 14 will be required by the variation in the types of telephone sets to be accommodated.

In Fig. 1, the conducting cord 17 connecting the telephone set to the line wires or to other apparatus is taken through the tubular portion of the shaft, sufficient slack being left between the desk stand and the upper part of the tubular arm to permit the telephone set to swing freely upon its bolt 11'.

By positioning the axis of the tubular arm 4 with respect to the axis of the pivotal bolt 2' so that the axis of the arm will lie above that of the bolt when the arm is in or approaches its horizontal or extreme position, the clearance between the arm and the desk surface 18 is increased as a minimum; by this means, an inconvenience of many existing telephone supports is avoided, since it is not necessary to remove objects upon the desk surface, such as large book 19 from the path of the arm to permit the telephone set to be brought into a desirable position for use; positioning the telephone set below the arm, the minimum height of the arm is further increased, and by shaping the arm in a bend, as at 4', the minimum height of the straight or main body portion of the arm is still further increased.

Having thus described our invention, what we claim as new and desire to secure by United States Letters Patent is:

1. In a telephone support, a fixed base block having a vertical post, a swivel member fitted on said post for horizontal rotation and having a vertical bearing face at its outer extremity, a hollow arm having an offset bracket at one end pivoted on said bearing face, so that the arm and bracket may rotate in vertical planes passing through the base block post, a compression spring within the arm with its lower end held at the lower end of the arm, and a compression member lying within the spring and approximately in the axis of the hollow arm, with its upper end bearing on the upper end of the spring, and its lower end tied to the base block swivel element at a point between the post and the bearing face pivot on the outer end thereof, together with means for supporting a telephone instrument from the end of the hollow arm, the construction and arrangement of the parts specified being such that when the arm is turned up into a vertical position, its axis will lie within its pivot, that is to say, toward the post or fixed support, and the compression member will at all times exert a straight pull between the upper end of the spring and the intermediate point on the swivel member.

2. In a telephone support, a fixed base block, a radial arm having universal bearings thereon so that its outer end may be moved in a surface approximating that of a sphere, a compression spring in the arm, and a compression member lying within the spring and extending from its upper end to a point fixed to the base block and lying above the center of vertical swing of the arm, together with a freely movable link suspension device attached to the end of the arm and adapted for engagement with the neck of a telephone set, whereby the same will be suspended freely from the arm, and in all its movements will exert a direct and constant pull on the compression spring.

3. In a telephone support, a fixed base block having a vertical post, a swivel member fitted on said post for horizontal rotation, a hollow arm horizontally pivoted to said swivel member and having its main body wholly displaced laterally out of line with said horizontal pivot, a spring within said arm connecting at one end with said arm, and having its opposite end freely movable with respect thereto, and a tension member for said spring connected at one end with the free end of said spring and at the other with a point on said swivel member fixed as respects said horizontal pivot and laterally displaced therefrom, but in substantial alinement with said arm when the said arm occupies its vertical position, together with a telephone set carried at the outer end of said arm.

4. A telephone support comprising a fixed base block having a vertical post, a swivel member fixed on said post for horizontal rotation thereabout, a hollow arm horizontally pivoted to said swivel member and having its main body when in normal position displaced laterally and to the rear of the vertical line passing through said pivot, a compression spring within said arm connecting at one end with said arm and having its opposite end freely movable with respect thereto, and a tension member connected at one end to the free end of said spring and at the other end to a point on said swivel member fixed as respects said horizontal pivot and displaced laterally and to the rear of the same, whereby it is given a position in approximate alinement with the main body of said arm when in normal position, together with a telephone set carried at the outer end of said arm.

5. In a telephone support, a fixed base block having a vertical post, a swivel member fitted on said post for horizontal rotation thereabout, a supporting arm horizontally pivoted to said swivel member and having its main body displaced when in normal vertical position laterally and to the rear of the vertical line passing through said pivot but substantially parallel there-

to, a spring within said arm, connecting at one end with said arm and having its opposite end freely movable with respect thereto, and a tension member for said spring connected at one end with the free end of said spring and at the other to a point on said swivel member fixed as respects said horizontal pivot but above and laterally and rearwardly displaced from said pivot, together with a telephone set carried at the outer end of said arm.

6. A telephone support comprising a fixed base block having a vertical post, a swivel member fitted on said post for horizontal rotation thereabout and having a horizontally arranged pivot on a line displaced laterally from said post, a hollow arm having a vertical normal position carried on said horizontal pivot and when in the said vertical normal position having its main body displaced laterally from the vertical line passing through said pivot, a spring within said arm connected at one end with the arm and having its opposite end freely movable with respect thereto, and a tension member for said spring connected at one end with the free end of said spring and at the other at a point on said swivel member fixed as respects said pivot but laterally displaced therefrom, said displacements of the main body of said arm in normal position and of the said fixed point of connection of said tension member being toward the vertical post from the horizontal pivot whereby the said post, the said point of connection of the said tension member to the swivel member, and the main body of the arm are brought substantially into alinement when the arm is in normal position, together with a telephone set supported at the outer end of said arm.

7. A telephone support comprising a fixed base block having a vertical post, and a swivel member fitted on said post for horizontal rotation thereabout, a hollow supporting arm horizontally pivoted to said swivel member but when in normal vertical

position having its main body displaced laterally of the vertical line passing through its pivot, a compression spring within the hollow of said arm connecting at one end with the said arm and having its opposite end freely movable with respect thereto, and a tension member for said spring connected at one end with the free end of said spring and at the other with a point on said switch member fixed as respects said horizontal pivot but laterally displaced therefrom and in substantial alinement with the main body of said arm when the arm is in its normal position, said spring being active to bias said arm to its normal vertical position throughout the movement of the arm from vertical to and from horizontal position, and said horizontal pivot of the arm having a friction on said hollow arm effective throughout said movements, together with a telephone set carried by said outer end of said arm.

8. In a telephone support, a fixed base block having a vertical post, a swivel member fitted on said post for horizontal rotation thereabout, an arm horizontally pivoted to said swivel member at a point in front of said vertical post and having its main body when upright wholly displaced laterally and to the rear of said horizontal pivot, and a spring biasing said arm to an upright position, said spring connected at one end with said arm and at the other end to a point on said swivel member fixed as respects said horizontal pivot but laterally and rearwardly displaced therefrom, whereby said supporting arm is continually drawn rearwardly and toward said vertical post.

Signed by us at Chicago, county of Cook and State of Illinois, in the presence of two witnesses.
